Primary Examiner—Freda Nunn*Attorney, Agent, or Firm*—Lawrence D. Cutter**[57] CLAIM**

The ornamental design for the digital simulation computer housing, as shown.

DESCRIPTION

FIG. 1 is a top front and right side isometric view of the digital stimulation computer housing showing our new design;

FIG. 2 is a right side elevational view thereof;

FIG. 3 is a left side elevational view thereof;

FIG. 4 is a front elevational view thereof;

FIG. 5 is a rear elevational view thereof; and,

FIG. 6 is a top plan view thereof.
